UNITED STATES PATENT OFFICE.

DAVID RAY BORLAND, OF MONTREAL, QUEBEC, CANADA.

TELEGRAPH-KEY.

SPECIFICATION forming part of Letters Patent No. 380,310, dated April 3, 1883.

Application filed February 24, 1887. Serial No. 228,787. (No model.) Patented in Canada February 17, 1887, No. 26,026.

To all whom it may concern:

Be it known that I, DAVID RAY BORLAND, of the city and district of Montreal, in the Province of Quebec, Canada, telegraph-operator, have invented certain new and useful Improvements in Telegraphic Keys—to wit, an Automatic Switch Attachment, (patented in Canada, No. 26,026, February 17, 1887;) and I hereby declare that the following is a full, clear, and exact description of the same, reference being made to the accompanying drawings, in which—

Figure 1 is a complete drawing of the automatic switch attachment annexed to a telegraphic key and in operation. Fig. 2 is a drawing of the switch and tension-spring, together with a section of the base of the key, showing the attachment of the tension-screw. Fig. 3 is a drawing of the lever of the automatic switch attachment, showing the roller and finger-piece by which it is operated. Fig. 4 is a drawing of the brass fastener with rubber handle, used to keep the key open when desired.

My invention is an attachment to a telegraphic key, used to open the key and close the same automatically, thus preventing the accidental leaving open of the key and consequent interference with the electric circuit and injurious 30 detention to traffic. It is composed of the following pieces, viz:

First. A lever (marked A' in the annexed drawings, and herein referred to as the attachment-lever) the fulcrum of which consists of a screw passing through the main lever of the key on the left-hand side immediately behind and below the finger-button. To one end of this lever—that is, the end farthest from the finger-button—is attached a roller, (marked A² in the drawings,) while the other end of the lever is cranked in such a manner as to permit of a piece of hard rubber or finger-piece (marked B in the drawings) being affixed in such a position as to overhang a portion of the finger-button.

Second. A small roller (marked A² in the drawings) attached by means of a steel pivot to the attachment-lever in such a manner as to play up and down the inclined side of a brass upright, (marked C in the drawings.)

Third. A hard-rubber finger-piece (marked B in the drawings) annexed to the front end

of the attachment lever, rounded upon the top, with the end so grooved as to fit the end of the finger used in pressing back the attachment-lever, and thus opening the switch.

Fourth. An upright piece of brass (marked C in the drawings) attached to the switch, tapering to the top, so that the inner side of it presents an inclined plane upon which the roller A² plays up and down, thus opening and closing the key.

Fifth. A tension-spring (marked E in the drawings) attached to an adjustable screw immediately in front of the right-hand center-post, the other end being attached to the inner or convex side of the switch. This spring renders the movement of the switch automatic by drawing it to, and so closing it immediately the pressure of the finger is withdrawn from the finger-piece B.

Sixth. A tension or adjustable screw (marked F in the drawings) immediately in front of the right-hand center-post, to which the tension-spring E is attached.

Seventh. A brass fastener (marked G in the drawings) with hard-rubber handle, one end of which is attached to the top of the main lever by means of a screw, and so adjusted as to swing over the attachment-lever when pushed back to open the key, and so to mechanically keep the switch open should the operator wish to leave the key open for testing or other purposes.

The automatic-switch attachment is operated by pressing the first finger against the finger-piece B, partly overhanging the finger-button. This lowers the farther end of the attachment-lever A', and the roller A², playing upon the inclined side of the brass upright C, presses back the switch D and opens it. It may be held in this position, and the key thus held open as long as required. If preferred in the case of very long messages, or when required for testing, the key may be mechanically kept open by means of the fastener G. When the pressure is removed from the finger-piece B, the tension-spring E draws in the switch D and closes it, the inclined side of the brass upright C pressing against the roller A², causing that end of the attachment-lever A' to rise to its normal position. The tension-spring E may at any time be adjusted by means of the tension-screw F.

The advantage and utility are that, the switch being rendered self-closing in its action, one of the principal causes of detention to railway traffic, as well as to ordinary commercial telegrams, becomes impossible. Through the accidental interference with the circuit by leaving open switches great detention and loss has occurred, as well as disastrous accidents. The switch closing automatically the moment the pressure is removed from the finger-piece renders this impossible. Its action is free, easy, and convenient, and by its use the best possible connection is obtained. It is adaptable to any description of key, and does not interfere in any way with the most rapid transmission.

I make no claim to the switch of the key, which is substantially as at present in use.

What I claim as my invention, and desire to secure by Letters Patent, is—

The automatic switch attachment composed of a lever, A', the fulcrum of which consists of a screw passing through the main lever of the key on the left-hand side immediately behind and below the finger-button, working by means of a roller, A², upon the inclined side of a brass upright, C, attached to the switch, thus opening the switch, as herein described, and of a tension-spring, E, one end of which is attached to an adjustable screw, F, in front of the right-hand center-post, the other being attached to the inner or convex side of the switch, by means of which the switch is automatically closed, the whole substantially as set forth.

Montreal, February 3, 1887.

DAVID RAY BORLAND.

In presence of—

P. GORMAN,

J. WENDELL ANDERSON.
